UNITED STATES PATENT OFFICE.

JOHN S. SURBAUGH, OF VINCENNES, INDIANA.

HANDLE AND BLADE CONNECTION.

Application filed September 17, 1921. Serial No. 501,319.

To all whom it may concern:

Be it known that I, JOHN S. SURBAUGH, a citizen of the United States, residing at Vincennes, in the county of Knox and State 5 of Indiana, have invented certain new and useful Improvements in Handle and Blade Connections, of which the following is a specification, reference being had therein to the accompanying drawing.

10 The present invention relates to handle and blade connections for use in shovels, scoops, spades and other tools, this invention being an improvement over the handle and blade connection disclosed in my Patent 15 No. 1,374,336 granted April 12, 1921.

The invention has for its object to improve and simplify the connection of the handle and blade or head of the tool, permitting either the blade or handle to be removed and replaced when worn out or damaged, thereby providing for economy in that either part of the tool can be replaced without discarding the remaining sound part.

25 Another object is to provide thoroughly efficient and convenient means for securing the handle member within the roll of the blade in a rigid and substantial manner, to withstand prying, torsional, leverage and 30 other strains to which the connection is subjected in use, and the connection being, at the same time, extremely simple and inexpensive.

A further object is the provision of such 35 a connection utilizing a single securing bolt or fastener for retaining the handle member within the roll and clamping said parts tightly together by the simple operation of tightening said bolt or member which has a 40 flexing or straightening movement to accomplish such results.

With the foregoing and other objects in view, which will be apparent as the description proceeds, the invention resides in 45 the construction and arrangement of parts hereinafter described and claimed, it being understood that changes can be made within the scope of what is claimed without departing from the spirit of the invention.

50 The invention is illustrated in the accompanying drawings, wherein—

Figure 1 is a perspective view of the shovel or scoop embodying the improvements.

55 Fig. 2 is a longitudinal vertical section

through the connection between the handle member and blade.

Fig. 3 is an enlarged cross section on the line 3—3 of Fig. 2.

Fig. 4 is a cross section similar to Fig. 3 showing a modification.

Fig. 5 is an elevation of another modified form of bolt or clamping member.

The invention can be used in shovels, scoops, spades and other tools, having a 65 similar blade, and, as shown, the blade 1 is of the "hollow back" type, such as used in shovels and scoops, said blade being provided with an upstruck roll 2 extending forwardly from its rear end and the roll, as 70 shown, has a fork 3 whose branches stiffen and reenforce the body of the blade to make it thoroughly rigid with the roll and back. A tubular handle member 4 is fitted within the roll 2, being preferably of sheet metal 75 having its longitudinal edges meeting at the bottom, and said tubular member 4 may be extended to constitute the shank, or a wooden shank or core 5 can be fitted within

80 said tubular member 4 as illustrated, it being apparent to those versed in the art, that the handle may be composed of a shank 5 fitted within the tubular member 4, or may be composed of a tubular metal member, similar to the member 4, or may be simply 85 a wooden shank as at 5, without using the tubular member 4. The construction illustrated, however, is preferable for several

reasons, in that the wooden and surrounding metal members reenforce and stiffen one 90 another to withstand the strains. The tubular member 4 is of a shape to fit snugly under the roll 2 against the sides and crown thereof, and is of a length to project rearwardly from under said roll. Transverse 95

rivets 6 and 7 or other similar securing elements extend through the member 4 and shank 5 for securing them together, the rivet 6 being located near the lower or outer end of the tubular member, and the rivet 100

7 at the rear end of the roll. The ends of the rivets 7 can extend from the tubular member 4, as disclosed in said patent, to abut against the rear end of the roll, as seen in Fig. 1, whereby to transmit the forward or downward longitudinal strains and pressure from the handle member to the rear end of the blade in an effective manner.

The roll 2 may be reenforced to stiffen 110

and strengthen same, as disclosed in said patent, by means of a liner plate 8 arched transversely to fit under and within the roll, and secured thereto by any suitable means. The reenforcing plate 8 will strengthen the roll, and can be used on the outside of the roll if desired, although it is preferably used underneath the roll so as not to obstruct the upper surface of the blade, 10 the function of said plate being to increase the thickness of the roll so as to resist the strains.

In order to secure the handle member within the roll, the opposite sides of the roll 15 are provided with the apertures 9, for the insertion of a transverse bolt 11 through said apertures under the handle member. The construction as described to this point is substantially the same as disclosed in said 20 patent, but instead of having the bolt or fastening member shift bodily toward the crown of the roll as in said patent, only the intermediate or central portion of the bolt is shifted for clamping the handle member 25 against and under the crown of the roll. This is accomplished, as shown in Fig. 3, by using an arcuate or bent bolt 11, which is bowed or bent away from the crown of the roll, and said bolt is of sufficiently small 30 diameter as to be flexible or resilient under the tensile strain to which the bolt is subjected when it is tightened for clamping the handle member to the blade. In other words, a bolt is used which is of sufficiently small 35 diameter so that it will spring and tend to straighten out when tightened under tensile strain, without distorting or damaging the blade.

The bolt 11, as shown in Fig. 3, has a 40 removable cotter pin or key 12 engaging therethrough near one end to be disposed at one side of the roll, and a nut 13 or other tightening means is engaged on the other terminal of the bolt to be disposed at the 45 opposite side of the roll. Said nut, when tightened, will apply a tensile strain to the bolt, which will straighten out the bolt more or less, and the handle member extending across the intermediate portion of the bolt 50 will be shifted by the bolt toward the crown of the roll for clamping the handle and blade tightly together. As shown, washers 14 are disposed between the sides of the roll and the nut 13 and key 12, and have convexed sides 55 bearing against the roll to permit of a slight tilting movement of said washers by the flexing movement of the bolt. By using the key or pin 12, instead of an ordinary head on the bolt, such pin or key can be driven out or 60 removed, when the nut 13 is loosened, in order that the bolt or rod 11 can be driven out through the apertures 9 toward the right as seen in Fig. 3, thereby avoiding the possible injury to the threads of the bolt where 65 the nut 13 is disposed, which might occur

if the bolt was driven out in the opposite direction by removing the nut 13. In this manner, the tensile strain applied to the flexible or bendable bolt or fastening member will flex or bend same toward a straight 70 line position, thereby shifting the intermediate portion of the bolt or member and handle member toward the crown of the roll, for tightly clamping the handle member between said bolt or member 11 and the 75 crown of the roll. This will clamp the handle member and crown of the roll together tightly throughout the length of their contacting surfaces, and the use of the single securing element will provide a thoroughly 80 rigid and substantial connection to withstand the various strains.

In order to reinforce and strengthen the handle where it is secured in the roll, an elongated reenforcing plate 17 is fitted in 85 a longitudinal vertical slot 18, cut in the shank 5 and extending from its forward or lowered end to a point adjacent to or beyond the rear end of the roll 2. The upper edge of the plate 17 bears against the upper portion of the tubular member 4, and the rivets 6 and 7 extend through said plate to secure it in place. The lower edge portion of the plate 17 is disposed between the edges of the member 4, and the lower edge of said 90 plate has a notched seat or portion 10 to engage and seat on the bolt or member 11, as seen in Fig. 2. This serves a double purpose, because the pressure from the bolt or member 11 is transmitted directly to the 100 plate 17 and thus distributed to the member 4 and shank 5 in an effective manner, and, furthermore, the notched seat or portion 10 engaging over the bolt 11 will prevent the longitudinal displacement of the handle and 105 blade relatively to one another, so as to lock them together when the bolt is tightened.

A modification is shown in Fig. 4, wherein the fastening or clamping member 11' is somewhat different than the resilient bolt 11 110 as shown in Fig. 3. The member 11' is curved or bowed away from the crown of the roll, the same as the bolt 11, and although flexible, is not resilient. The member 11' is composed of the terminal portions 115 20 and 21 connected by links 23 pivoted to one another and to the portions 20 and 21, so that the sections or portions of the member can swing relatively to one another, and the links 23 provide a short chain in the 120 member 11' to extend under the handle. When the nut 13 is tightened, the member 11' will tend to straighten out, the same as the member or bolt 11, for clamping the handle against the crown of the roll, the 125 plate 17 engaging on one of the links 23. As shown, the member 11' has a head 12' on the portion 20 to bear against one side of the roll, instead of using the removable pin or key 12, because, when the nut 13 is removed, 130

there is no tension on the member 11', and it can be readily withdrawn through the apertures 9 without difficulty or injury to the screwthreads.

5. Fig. 5 shows another form of bolt or member that can be used for clamping the handle in the roll. This bolt or member 11" comprises the sections 24 and 25 pivotally connected, as at 26. The nut 13 is threaded 10 on the section or portion 25, and the section 24 has the slot 27 to receive the pin or key 12. This bolt or member 11" is bent or bowed away from the crown of the roll, and the pivot 26 permits the sections 24 and 25 15 to move toward a straight line position when the nut 13 is tightened. By using the pivot or hinge 26, the bolt 11" can be of larger diameter, and need not be resilient.

The convexed or tapered sides of the washers and heads on the bolts or securing members are seatable in the apertures in the sides of the rolls, whereby to permit of the tilting or swinging movements of said parts, without the terminals of the bolts or securing 25 members shifting out of position toward or away from the crowns of the rolls.

Having thus described the invention, what is claimed as new is:—

1. A tool including a blade having a roll, a 30 handle member to fit within said roll, and flexible securing means extending across the roll and arranged to have a straightening out movement toward the crown of the roll when tightened, for clamping the handle member within the roll.

2. A tool including a blade having a roll, a handle member to fit within the roll, and securing means extending through the sides of the roll and bent or bowed away from 40 the crown of the roll to have a straightening out movement when tightened, for clamping the handle member in the roll.

3. A tool comprising a blade having a roll for receiving a handle member, and flexible 45 securing means extending across the roll and having a straightening out action when tightened for clamping the handle member in the roll.

4. A tool comprising a blade having a roll 50 for receiving a handle member, and flexible

securing means extending through the sides of the roll and bowed or bent away from the crown of the roll to have a straightening out movement when tightened, for clamping the handle member in the roll. 55

5. A tool comprising a blade having a portion for receiving a handle member, and a curved or bent securing member extending through said portion and adapted to be tightened to have a straightening-out action 60 for clamping the handle member to the blade.

6. A tool comprising a blade having a roll for receiving a handle member, and a securing member extending through the sides of the roll and curved or bent away from the 65 crown of the roll and having means for applying tensile strain to said member to give it a straightening out action for clamping the handle member in the roll.

7. A tool comprising a blade having a roll, 70 a securing member extending through the sides of the roll, said member being flexible and bowed or bent away from the crown of the roll, and means on said member for bringing it under tension and giving said 75 member a straightening-out action for clamping the handle member in the roll.

8. A tool including a blade having a roll, a handle member fitted within the roll, a plate secured within said handle member, 80 and securing means extending through the sides of the roll and having a straightening-out action when tightened to clamp the handle member in the roll, said plate having a portion to engage said securing means. 85

9. A tool including a blade having a roll, a handle member to fit in said roll, a plate secured in said handle member, a flexible securing member extending through the sides of the roll and having means for tightening it, said member being bent or bowed away from the crown of the roll to have a straightening-out action when tightened for clamping the handle member in the roll, said plate having a notched portion to engage 90 over said securing member. 95

In testimony whereof I hereunto affix my signature.

JOHN S. SURBAUGH.
